UNITED STATES PATENT OFFICE.

TOM DRAKE AND JOSEPH GRACIE WINTER FIELD, OF ALTRINCHAM, ENGLAND, AS
SIGNORS TO LINOTYPE AND MACHINERY LIMITED, OF LONDON, ENGLAND, A
BRITISH COMPANY.

ESCAPEMENT-ACTUATING MECHANISM OF TYPOGRAPHICAL COMPOSING MACHINES.

Application filed July 26, 1922. Serial No. 577,528.

To all whom it may concern:

Be it known that we, TOM DRAKE and JOSEPH GRACIE WINTER FIELD, both subjects of the King of the United Kingdom of 5 Great Britain and Ireland, and residing at Linotype and Machinery Works, Altrincham, in the county of Chester, England, have invented new and useful Improvements in or Relating to Escapement-Actuating Mechanism of Typographical Composing Machines, of which the following is a specification.

This invention relates to typographical composing machines of the construction 15 known commercially under the trade mark "linotype" and kindred machines, and it has for its object to provide new or improved means whereby typographical elements of the same typographical significance contained in separate magazine channels can be released from those channels 20 in alternation by successive actuations of one and the same finger key.

The expression "typographical elements" 25 for the purposes of this specification is intended to include all such devices as are usually stored in the magazines of the before-mentioned machines, whether those devices be provided with formative cavities 30 for producing printing faces or be in the form of quads or spaces. As, however, the invention is especially applicable for use in connection with what are known as the double "e" channels the following description 35 is restricted to that application and the aforesaid typographical elements are considered to be matrices appropriate to that character. It is further herein considered that the two channels in question are juxtaposed although there are already known 40 power-transmission devices by which matrices from channels situated at a distance apart can be alternately released by successive actuations of one and the same key, 45 and for that reason the present invention is intended to include all such varied arrangements.

The invention will now be described by reference to the accompanying drawings 50 in which:

Figure 1 is a left-hand side elevation of sufficient of a typographical composing machine to illustrate the embodiment there-

in of one constructional form of the present improvements, and

Figures 2 and 3 are front elevations of Figure 1 showing the devices in respectively different positions.

In the constructional form represented in the drawings, there is a single key-rod 1 60 alternately brought into operation with two escapement rods 2, 3, as shown respectively in Figures 2 and 3, appertaining to the two "e" channels of the magazine, said key-rod 1 being automatically operated by a cam 65 yoke, when the latter, in the well-known manner, is released by the respective key-lever.

As the just mentioned magazine, cam-yoke and key-lever form no part of the 70 present invention, they have been omitted from the drawings.

The key-rod 1 is held in normal position by a spring 4 which as shown in Figures 2 and 3, is so arranged as to tend to draw 75 said key-rod towards the left, so as to cause a pin 5 on the latter to bear against the edge of a ratchet disc or wheel 6.

As a matter of fact it is to a rearward extension of the pin 5, that the upper end 80 of the spring 4 is attached, the lower end of said spring being anchored to a fixed rail 7, by a pin or hook 8.

The teeth 6^a, or the spaces or recesses 6^b between the teeth, of the ratchet wheel 6, 85 are of such shape or size that successive angular movements of said wheel, due to successive operations of the key-rod 1, present surfaces which hold or direct the pin 5 in paths appropriate to the actuation of 90 the respective escapement rods. Thus, in certain angular positions of the wheel such as that indicated in Figure 2, the wheel surfaces engaged by the pin 5, viz:—those identified by the references 6^c are substantially vertical, and operation of the respective key-lever serves to actuate say the right-hand escapement rod 2 of the two (2, 3) appropriate to that key-lever. During this same operation a spur 6^d on the 100 wheel 6 is presented in the path of the pin 5 so that when this pin, during its ascent, engages the said spur, it turns the wheel 6, and inclines the above particularized pin-guiding surface 6^e, so that during the next 105 ensuing descent of the key-rod 1, the pin

- 5 rides over the said surface until it passes the lower end thereof at which juncture it is drawn by the spring 4, into the next following recess 6^b of the wheel with the 5 upper end of the key-rod 1 in engaging alignment with the left-hand rod 3 of the two pertinent escapement rods as shown in Figure 3. During the next ensuing operation of the key-rod 1, the pin 5 engages 10 with the top of the respective recess 6^b and turns the wheel 6 sufficiently to bring a succeeding pin-guiding surface 6^c into substantially vertical position, and the key-rod 1 actuates the before-mentioned left-hand escapement rod 3, and, during the next following descent of the key-rod, the pin 5 passes out of the recess 6^b and over, and to the underside of, the respective spur 6^d with which the said pin engages, for again 15 turning the wheel as before described.

A suitable device such as the adjustable friction or brake spring 9 is provided for exerting on the wheel 6 just sufficient friction to prevent the rotation of the latter, excepting at such times as it is positively rotated by the key-rod pin 5.

10 indicates one of the ordinary key-rods, which, however, constitutes no part of the present invention. It is to be noted that 20 so far as concerns the actuation of the disc 6 by the key-rod 1, it is immaterial whether the before described pin 5 is formed separate from, and attached to that rod, or formed as an integral part of the said rod, both of which arrangements are intended to 25 be included in the following claims.

Having described our invention, we declare that what we claim and desire to secure by Letters Patent is:—

- 40 1. In or for the escapement-actuating mechanism of a typographical composing machine wherein a single key-rod at successive actuations is caused to operate different escapement rods, a disc or wheel adapted 45 to be partially rotated directly by the key-rod at each actuation of the latter and at different angular positions to present respectively different guiding surfaces which cause the said key-rod to engage respectively 50 different escapement rods.

2. In or for the escapement-actuating mechanism of a typographical composing machine wherein a single key-rod at successive actuations is caused to operate different escapement rods, a ratchet disc or wheel adapted to be partially rotated at 55 each actuation of the key-rod by the engagement of the latter with the toothed portion of the disc or wheel and having successive interdental spaces of respectively 60 different contour.

3. In or for the escapement-actuating mechanism of a typographical composing machine wherein a single key-rod at successive actuations is caused to operate dif-

ferent escapement rods, a ratchet disc or wheel according to claim 2, characterized by alternate interdental spaces having like contours.

4. In or for the escapement-actuating mechanism of a typographical composing machine wherein a single key-rod at successive actuations is caused to operate different escapement rods, the combination with the key-rod of a ratchet disc having successive interdental spaces of respectively different contour, a pin fast to the key-rod and means adapted to hold said pin constantly in contact with the periphery of the disc.

5. In or for the escapement-actuating mechanism of a typographical composing machine wherein a single key-rod at successive actuations is caused to operate different escapement rods, the combination with the key-rod of a ratchet disc having interdental spaces of different contours arranged in alternation, a pin fast to the key-rod and a spring adapted to hold said pin constantly in contact with the periphery of the disc.

6. In or for the escapement-actuating mechanism of a typographical composing machine wherein a single key-rod at successive actuations is caused to operate different escapement rods, the combination with the key-rod of a ratchet disc having successive interdental spaces of respectively different contour, a brake adapted to prevent accidental rotation of the disc, a pin fast to the key-rod and a spring adapted to hold said pin constantly in contact with the periphery of the disc.

7. In or for the escapement-actuating mechanism of a typographical composing machine wherein a single key-rod at successive actuations is caused to operate different escapement rods, the combination with the key-rod of a ratchet disc having interdental spaces of different contours arranged in alternation, an adjustable brake spring adapted to prevent accidental rotation of the disc, a pin fast to the key-rod and a spring adapted to hold said pin constantly in contact with the periphery of the disc.

8. In or for escapement-actuating mechanism of a typographical composing machine, the combination with a plurality of escapement rods and a single key-rod adapted to make direct contact with and operate said rods in alternation, of a disc or wheel positively engaged by the key-rod and adapted to be partially rotated by each actuation of the latter, guiding surfaces for the key-rod at different angular positions on the periphery of the disc, said surfaces being at such relatively different radial distances from the axis of the disc as to hold the key-rod in operative register with re-

spectively different escapement rods, and means operative to retain the key-rod resiliently in sliding contact with the periphery of the disc.

- 5 9. In or for escapement-actuating mechanism of a typographical composing machine, the combination with a plurality of escapement rods and a single key-rod adapted to make direct contact with and operate
- 10 said rods in alternation, of a ratchet disc or wheel positively engaged by the key-rod and adapted to be partially rotated by each actuation of the latter and the successive interdental spaces of which are of respec-
- 15 tively different contour and the walls of which are adapted to hold the key-rod in operative register with respectively different escapement rods, and means operative to hold the key-rod resiliently in slid-

ing contact with the periphery of the 20 ratchet disc.

10. In or for escapement-actuating mechanism of a typographical composing machine, the combination with a plurality of escapement rods and a single key-rod adapt- 25 ed to make direct contact with and operate said rods in alternation, of a ratchet disc or wheel positively engaged by the key-rod and adapted to be partially rotated by each actuation of the latter and the alter- 30 ate interdental spaces of which have like contours, and means operative to retain the key-rod resiliently in sliding contact with the periphery of the disc.

In testimony whereof we have affixed our 35 signatures hereto.

TOM DRAKE.

JOSEPH GRACIE WINTER FIELD.
